AI B. SHAW, OF SANTA MONICA, CALIFORNIA, ASSIGNOR, BY DIRECT AND MESNE ASSIGNMENTS, TO DOROTHY M. STOREY, OF SANTA MONICA, CALIFORNIA

PAPER CLIP OR FASTENER

Application filed November 21, 1928. Serial No. 320,980.

This invention relates to paper clips or fasteners.

It is a general object of the invention to provide a temporary securing clip of simple and effective construction; which can be securely clamped in holding position; which is easily operable to engage and disengage a bunch of sheets, and which has a gripping means and a clamping device operative thereon to accomplish a setting of the gripping on interposed sheets.

A further object is to provide a double jawed, self-opening gripping means and an inseparable, resilient, closing vice therefor, and which is capable of adaptability to variant thicknesses of stacks of sheets.

An important object is to provide a safety paper fastener of such form and construction that it will be snug up to an edge of interposed sheets so that these may be filed without disadvantageous obstruction.

Another purpose is to provide a reliably adhering or safe fastener which is of low cost; of light weight, is substantial in structure and does not destructively lacerate the gripped paper sheets.

There are additional objects, advantages and features of construction as will be made manifest in the ensuing description of embodiments herewith illustrated; it being understood that modifications, variations, and adaptations may be resorted to within the scope, principle and spirit of the invention as it is hereinafter claimed.

Figure 1 is a perspective of an applied fastener.

Figure 2 is an end elevation of a closed fastener.

Figure 3 is a cross-section of the device in opened position.

Figure 4 is a plan of a fastener with a perforate leaf gripping means.

Figure 5 is a side view of a modified form of leaf vice.

Figure 6 is an end view of a modified form of fastener.

Figure 7 is a plan of the applied modified form of Figure 6.

The fastener consists of two principal pieces one of which includes a gripping means

and the other an associated vise to close the gripping means.

The gripping means is shown as comprising an upper leaf 2 and a lower leaf 5 which are of one piece of spring sheet metal folded medially to bring the leaves 2-5 into opposed relation and normally springing to an open, divergent position, Figure 3. The leaves may be perforate at 6, Figure 4, or imperforate as in Figures 1, 2, and 3. The bow of the fold 7 provides for a hinged effect during closing of the leaves 2-5.

The leaf 2 has an upwardly embossed crescent ridge 3 and opposed to this is a similar ridge 4 on the lower leaf 5; these ridges tending to telescope when the leaves are brought together and therefore taking a firm interbending grip on interposed sheets S.

If desired the crown of the ridge 4 may have slight impaling prongs 8.

For the purpose of positively closing and clinching the leaves 2-5 on interposed sheets a clamping device in the form of a staple shaped vise with a pivot bar 11 is turnably and perpendicularly pivoted in the fold 7 so that its jaws 12-13 can be swung around and onto the ridge 3 and the bottom leaf respectively; the distance between the jaws 12-13 being such that the leaves will be moved toward each other as the jaws are forced onto the leaves, as in Figures 1 and 7. The open rolled fold 7 forms an open-ply, back-bone whose spaced plies constitute well spaced supports for the diametrically disposed pivot 11.

While the jaws 12-13 of the vise are stiff enough to hold the leaves closed on a stack, the jaws are preferably formed of spring wire and may yield to compensate for over-thick stacks of sheets. If desired the top jaw 12 may have a hump or loop 14 for finger purchase.

In the modified form of fastener of Figures 6 and 7 the leaves 2-5 have each an outwardly embossed ridge 3^a and 4^a to be engaged by the vise jaws 12-13. In this form one leaf has prongs 8^a; opposite apertures 6^a, to impale sheets in the fastener.

What is claimed is:

A clip or fastener including opposed grip-

ping leaves connected by a folded, open-ply back-bone bearing forming part, and a vise consisting of a U-shaped wire spring whose cross-bar is straight and which is journaled as a diametrical pivot in the widely spaced plies of the folded back-bone so that maximum bearing length is provided along the pivot bar to secure support for the bar when the arms of the spring are in clamping position; the ends of the gripping leaves being provided with opposed concavo-convex gripping ridges lying in the sweep of the ends of the clamp arms.
